(57) **CLAIM**

The ornamental design for a combined container and label, as shown and described.

DESCRIPTION

FIG. 1 is a front view of the label portion of our new design for a combined container and label;

FIG. 2 is a front view of an alternate embodiment thereof;

FIG. 3 is a perspective view of a combined container and label incorporating our new design;

FIG. 4 is a front elevational view thereof;

FIG. 5 is a rear elevational view thereof;

FIGS. 6 and 7 are side elevational views thereof;

FIG. 8 is a top plan bottom view thereof; and

FIG. 9 is a bottom view thereof;

FIG. 10 is a perspective view of an alternate embodiment of a combined container and label incorporating our new design;

FIG. 11 is a front elevational view thereof;

FIG. 12 is a rear elevational view thereof;

FIGS. 13 and 14 are side elevational views thereof;

FIG. 15 is a top plan bottom view thereof; and,

FIG. 16 is a bottom view thereof.

The broken lines shown in the drawings depict environmental subject matter only and form no part of the claimed design.
